UNITED STATES PATENT OFFICE.

MONTE WELSH, OF SAN ANTONIO, TEXAS.

PHOTOGRAPHIC-PRINTING APPARATUS.

1,186,719.

Specification of Letters Patent. Patented June 13, 1916.

Application filed June 25, 1915. Serial No. 36,319.

To all whom it may concern:

Be it known that I, MONTE WELSH, a citizen of the United States, residing at San Antonio, in the county of Bexar and State 5 of Texas, have invented a new and useful Photographic-Printing Apparatus, of which the following is a specification.

The present invention appertains to photographic printing apparatus, and aims to 10 provide a novel and improved appliance for printing photographs or positives from negatives, either film or plate.

It is the object of the invention to provide a photographic printing apparatus 15 comprising a unique assemblage of the component parts, and improved generally in its details, whereby the utility and efficiency of the appliance is enhanced, the apparatus incorporating novel instrumentalities which 20 render the printing operation easy and efficient.

With the foregoing and other objects in view which will appear as the description proceeds, the invention resides in the combination and arrangement of parts and in 25 the details of construction hereinafter described and claimed, it being understood that changes in the precise embodiment of the invention herein disclosed can be made 30 within the scope of what is claimed without departing from the spirit of the invention.

The invention is illustrated in the accompanying drawings, wherein:—

Figure 1 is a plan view of the apparatus, 35 the electrical circuit being illustrated diagrammatically. Fig. 2 is a side elevation of the apparatus. Fig. 3 is an end view of the apparatus. Figs. 4 and 5 are vertical sections of the negative holder taken on the 40 lines 4—4 and 5—5, respectively, of Fig. 1. Fig. 6 is a horizontal section of the negative holder taken on the line 6—6 of Fig. 2. Fig. 7 is an edge elevation of the presser block for holding the sensitized paper or sheet, 45 portions being broken away. Fig. 8 is a lower edge view of the presser block. Fig. 9 is a sectional detail of a means for mounting the presser block, the section being taken on the line 9—9 of Fig. 2.

50 The apparatus is carried by a suitable base 1, which is equipped between its ends with an upstanding negative holder 2 having the opening 3 adjacent its upper end for the passage of the light rays through the nega-

tive. A transparent panel 4 of glass or 55 equivalent material is secured to the front side of the holder 2 so as to extend across the opening 3, detachable clips 5 being carried by the front sides of the holder 2 which overlaps the panel 4 and hold it removably 60 in position.

As a means for holding a film negative across the opening 3 and panel 4, upwardly projecting resilient strips 6 have their lower end portions secured to the front side of the 65 holder 2 adjacent the edges of the said holder, the front side of the holder being provided adjacent its side edges with vertical grooves 7 receiving the rear curved sides of the strips 6. The strips 6 are arranged at the side edges of the panel 4. A second pair of upwardly projecting resilient strips 8 rest against and have their lower ends secured to the strips 6, and have their upper end portions or terminals free and 70 tending to swing against the upper terminals of the strips 6. The strips 6 and 8 form a combined mask and film holder. A pair of bolts or spindles 9 are engaged slidably through the strips 6 and the holder 2 below 75 the opening 3, and have heads 10 seating against the strips. Nuts 11 are threaded upon the rear ends of the bolts 9, and coiled wire expansion springs 12 are disposed between the holder 2 and nuts 11, whereby the 80 springs 12 tend to move the strips 6 against the holder 2. The nuts 11 may be adjusted 85 for regulating the tension of the springs 12.

Various masks may be used upon the holder 2. Thus, a mask 13, preferably 90 constructed of thin sheet metal, may be inserted downwardly between the upper terminals of the strips 6 and 8, as seen in Fig. 5, so as to be clamped between said strips, across the opening 3 and panel 4, 95 and the mask 13 is provided with a forwardly offset portion 14 providing a socket for receiving a glass or plate negative. This portion 14 has an opening 15 of restricted area, to define the border of the 100 print or positive, the mask 13 being opaque, and the rays of light only passing through the restricted opening 15, as will be obvious. A mask 13', somewhat similar to the mask 13, may be used in place thereof, for holding a cut film negative, the offset portion 14' extending completely between the upper and lower edges of the mask to receive 105

the cut film negative and having the opening 15'. The mask 13' is seen in Figs. 2, 4 and 6. The masks being of metal will not fray, and form an even border. The masks may be readily replaced by one another, and any number of masks may be employed interchangeably.

When a film negative 16 is employed, the same is slipped downwardly between the strips 6 and holder 2, so that the strips 6 will hold the negative 16 against the panel 4 within the grooves 7, to prevent the displacement of the negative during the printing operation. When a cut film is employed, it is supported within the mask 13' by a resilient strip 17 having the bent back terminals 18 adapted to be snapped around the side edges of the holder 2 at the lower edge of the opening 13, whereby the intermediate portion of the strip 17 bears against the panel 4 and the holder 2 immediately under the lower edge of the mask 13', to prevent the cut film from dropping downwardly out of the offset or socket portion 14' of the mask.

The holder for the sensitized paper or sheet, embodies a leaf or plate 19 having its lower end hinged upon the base 1 immediately in front of the holder 2, and a second leaf or plate 20 has its lower end hinged to the upper free end of the leaf 19. The leaf 19 projects upwardly to a point adjacent the opening 3, while the leaf 20 is adapted to be swung upwardly against the mask to coincide with the opening 3. The leaf 20 carries a presser block or head 21 provided with means for gripping or holding the sensitized paper, and this presser block 21 is mounted upon and carried by a yieldably mounted plate 22 having a plurality of stems 23 projecting therefrom and working slidably through the leaf 20. Nuts or stops 24 are threaded upon the stems 23 and seat against the leaf 20 at that side of said leaf opposite the presser block 21, to limit the movement of the presser block away from the leaf 20, and coiled wire expansion springs 25 are disposed upon the stems 23 between the presser block 21 and leaf 20 for yieldably moving the presser block away from said leaf and toward the negative holder 2. The upper and lower edges of the plate 22 are provided with guides 26 for receiving the flanges 27 with which the presser block 21 is provided, whereby the presser block 21 may be slid laterally or sidewise into and out of engagement with the plate 22. This allows the presser block to be readily removed and replaced. The guides 26 are each provided at one end with an inturned ear or stop 28 for limiting the movement of the flanges 27 when the presser block 21 is slid into proper position, and a spring catch 29 is carried by one of the guides 26 for snapping into

engagement with the respective flange 27 for holding the presser block removably in position, since the catch 29 may be manually released when it is desired to remove the block 21.

The means for moving or swinging the leaf 20 and presser block carried thereby embodies a rock shaft 30 journaled within suitable bearings 31 carried by the base 1, the inner end of the shaft 30 being provided with a crank arm 32 connected by means of a link 33 with the leaf 20. The other end of the shaft 30 has a crank arm 34, to the free end of which is pivotally engaged a handle or lever 35. The handle or lever 35 is engaged between its ends to the arm 34, and the rear end or short arm of the handle or lever 35 is connected by a link or hinge leaf 36 with the base 1 in rear of the shaft 30. When the handle 35 is raised, to raise the arm 34, the arm 32 which is arranged at an angle with the arm 34, is swung downwardly onto the base 1, to pull the link 33 and the leaf 20 downwardly to inoperative position, as seen in full lines in Fig. 2. When the handle 35 is forced rearwardly and downwardly, to correspondingly move the arm 34, the arm 32 will be swung upwardly and rearwardly to correspondingly swing the leaf 20 and presser block 21, the presser block 21 being brought forcibly against the negative holder 2.

The gripping means carried by the presser block 21 embodies a spring pressed plate 37 slidably carried by one side edge of the presser block 21, and having an inturned flange 38 overhanging the respective edge portion of the block 21, suitable expansion springs 39 being disposed between the plate 37 and block 21 for yieldably moving the flange 38 away from the block. The gripping means also embodies a second plate 40 extending slidably against the lower edge of the presser block 21, and provided with an angularly extending flange 41 overhanging the block. The plate 40 has oblique or diagonal slots 42 through which pins or guide elements 43 are engaged, said pins being fixedly engaged to the block 21, whereby when the plate 40 is slid longitudinally, it will cause the flange 41 to move to and from the block 20 for gripping and releasing the sensitized paper. A coiled retractile spring 44 connects the plate 40 and block 21 for normally carrying the plate 40 in such a direction, as to move the flange 41 against the presser block for gripping the sensitized paper.

Means are provided for moving the plate 20 against the tension of the spring 44, when the holder for the sensitized paper is returned to inoperative or initial position, and to this end, a rock shaft 45 is journaled to one side edge of the presser block 21, and is

provided at one end with a crank arm 46 which is connected by a link 47 with the respective end of the plate 40, so that when the shaft 45 is rocked, the plate 40 will be reciprocated. The other end of the shaft 45 has an angularly extending arm or tappet 48 which is adapted to bear upon a stop 49 carried by the base or frame 1, whereby when presser block 21 is swung back to initial position, as seen in full lines in Fig. 1, the arm 48 in striking the stop 49 will cause the shaft 45 to be rotated in such a direction, as to force the plate 20 against the tension of the spring 44, and to thereby move the flange 41 away from the block 21.

A spring catch 50 is carried by the base 1 to engage and hold the handle 35 when the handle is depressed, whereby the presser block 21 may be held against the negative holder 2 for any length of time, without the necessity of the operator holding the handle 35 depressed. The catch 50 may be readily released from the handle 35 to allow said handle to be raised after the sensitized paper has been exposed to the light rays for the required time.

A lamp 51 is carried by the rear end of the base 1 for furnishing the light rays, and means is employed for cutting off the light rays from the negative holder, during the time that the presser block 21 is swung away from the negative holder for removing the exposed sensitized sheet, and while the new sensitized sheet is being inserted. Thus, an upstanding frame or standard 52 is carried by the base 1 in rear of the holder 2, or between said holder and lamp 51, and a swinging shutter 53 is hinged to one side edge of the frame or standard 52. This shutter 53 is preferably constructed of red glass, whereby when the shutter is closed, it will allow the red rays to pass therethrough, in order that the operator may conveniently remove and replace the sensitized paper without exposing the same to the active rays of light.

As a means for automatically operating the shutter 53 when the presser head is operated, a longitudinal rock shaft 54 is journaled upon the base 1 adjacent one side edge thereof, and is provided at its rear end with an angularly extending crank arm 55 which has its free end connected by means of a link 56 to an angularly extending arm 57 attached to the shutter 53, so that when the shaft 54 is rocked, it will swing the shutter 53 to open and closed positions. The shaft 54 is operated by the handle 35, and to this end, the forward end of the shaft 54 has an angularly extending arm or tappet 58 lying below the handle 35, and arranged to be depressed when the handle 35 is depressed, to thereby rock the shaft 54 in such a direction, as to swing the shutter 53 to open position when the presser block 21 is moved against the negative holder. Thus, the

shutter 53 is opened when the sensitized paper is carried against the negative holder, to allow the active light rays to penetrate the negative and act upon the sensitive chemical of the sensitized sheet of paper. As soon as the sensitized paper has been exposed the required amount of time, the handle 35 is raised, and this will immediately release the arm 58, so that the said arm will be raised by the leaf spring 59 carried by the base 1, to immediately close the shutter 53, as soon as the presser block 21 starts to leave the negative holder 2. This provides for the accurate exposure of the sensitized paper, and avoids an over exposure.

Instead of providing the shutter 53, the lamp 51 may be controlled, so that it is lighted and extinguished automatically. When the lamp 51 is controlled, the same is preferably in the form of an electric incandescent lamp interposed in the electrical circuit 60, said circuit having a push button switch 61 carried by the base 1 below the handle 35, whereby when the said handle is depressed, the switch 61 will be closed thereby to close the circuit 60 and light the lamp 51 when the sensitized paper is brought against the negative holder. As soon as the handle 35 is raised to return the presser block 21 to initial position, the switch 61 is released, to extinguish the lamp 51.

As above stated, either of the means for controlling the projection of light rays through the negative may be employed, as desired or necessary. The spring 59 not only serves to raise the arm 58 for normally closing the shutter 53, but also serves to raise the handle 35 from its depressed position, in order that when the catch 50 is released, the spring 59 will immediately raise the lever or handle 35 as well as shutting the shutter 53. The handle or actuating member 35 not only controls the movements of the presser block or sensitized paper holder but also controls the shutter 53 or lamp 51.

In operation, supposing the negative from which the prints are desired, is properly applied to the holder 2, as above indicated, by raising the handle 35, the leaf 20 is swung downwardly and forwardly to carry the presser block 21 to such a position, as seen in full lines in Fig. 2, that the exposed sheet may be readily moved and replaced by a new one. The flange 38 of the plate 37 is normally moved away from the block 21 under the influence of the springs 39, and the arm 48 of the shaft 45 in bearing upon the stop 49 will move the flange 41 away from the block 21, so that when the presser block 21 is returned to initial position the exposed sheet may be readily removed, and the new sheet may be readily placed upon the presser block under the flanges or jaws 130

38 and 41. During the time that the sensitized paper or sheet is being removed or replaced, the shutter 53 is closed, or the lamp 51 is extinguished, to avoid the undesired exposure of the sensitized paper. Then, when the handle 35 is depressed for bringing the sensitized sheet against the negative holder, as soon as the presser block 21 starts upwardly, the arm 48 will leave the stop 49, 10 and this will immediately bring the spring 44 into play for moving the flange 41 toward the block 21 to clamp the sensitized sheet. The sheet is thus held securely upon the block 21, while the block is being moved 15 against the negative holder, and this prevents the centrifugal action from throwing the sensitized sheet out of position. When the presser block 21 is brought against the negative holder, the flange 38 will be moved 20 toward the block 21 to also clamp and hold the sensitized sheet securely in position against the presser block 21. It is preferable to face the presser block 21 with soft rubber or equivalent yieldable material, in 25 order that the sensitized sheet will be properly pressed against the mask and negative. It is to be noted, in this connection, that the presser block 21 is yieldably supported by the leaf 20, in order that when the leaf 20 30 is forcibly moved toward the negative holder 2, the block 21 may yield relatively to the leaf 20, to properly bear against the negative holder. The leaf 19 allows the leaf 20 to shift when the leaf 20 is swung upwardly, 35 in order that the presser block may be properly brought against the negative holder. The handle 35 is held depressed by the spring catch 50, and as soon as the sensitized sheet has been exposed the required length 40 of time, the catch is released, and the handle 35 will be raised by the spring 59, it being understood, of course, that when the handle 35 is depressed to bring the sensitized sheet against the negative holder, the lamp 45 51 is lighted, or the shutter 53 is opened, to allow the light rays to penetrate the negative for acting upon the sensitized sheet, so that when the catch 50 is released, the spring 59 not only raises the handle 35, but also 50 closes the shutter 53, or allows the switch 61 to open for extinguishing the lamp 51.

From the foregoing, taken in connection with the drawings, it is believed that the advantages and attributes of the present apparatus will be obvious to those versed in the art, without further comment being necessary.

The shutter 53 is preferably constructed of some unbreakable material, such as fabric or celluloid, and is of the proper density to permit of the penetration therethrough of enough non-actinic light rays to allow the operator to judge the density of the negative in order to determine the amount of 65 time the sensitized paper should be exposed.

Having thus described the invention, what is claimed as new is:

1. In a printing apparatus, a base, an up-standing negative holder carried thereby, a leaf hinged upon the base adjacent said holder, a second leaf hinged upon the first mentioned leaf, a presser block yieldably carried by the second leaf to bear against the negative holder and having sensitized paper holding means, and means for swinging said second leaf to and from the negative holder. 70 75

2. In a printing apparatus, a base, an up-standing negative holder carried thereby, a leaf hinged upon the base adjacent said holder, a second leaf hinged upon the first mentioned leaf, a presser block yieldably carried by the second leaf to bear against the negative holder and having sensitized paper holding means, a rock shaft journaled 80 85 upon the base and having an arm, and a link connecting said arm and second leaf. 85

3. In a printing apparatus, a negative holder, a member movable to and from said holder, a plate having stems slidable 90 through said member, spring means between said plate and member, stops carried by the stems to bear against said member for limiting the movement of said plate away from said member, said 95 member having guides, a presser block having flanges fitting in said guides, means for holding said flanges within said guides, and means for moving said member to and from the negative holder, to bring 100 the presser block against and away from the negative holder. 100

4. In a printing apparatus, a presser block, a plate assembled therewith, one of said parts having oblique slots and the other 105 having elements working in said slots, the plate having a flange movable to and from the block, a spring connecting the plate and block for moving said flange toward the block, a negative holder to and from which the presser block is movable, a rock shaft carried by the block and having a pair of arms, a link connecting one of said arms and plate, and a stop against which the other arm is arranged to strike when the 110 block is moved away from the negative holder, so that said plate is moved against the tension of the spring to move the flange away from the block. 115

5. In a printing apparatus, a presser 120 block, a plate assembled therewith having a flange, one of said parts having oblique slots and the other having elements working in said slots whereby when the plate is moved longitudinally its flange is moved 125 toward or away from the block, a spring connected to said plate for moving said flange longitudinally and toward said block, a negative holder to and from which the presser block is movable, and means where- 130

by when the presser block is moved away from the negative holder to initial position, the said plate is moved to move said flange away from the presser block.

6. In a printing apparatus, a negative holder having an opening, a pair of resilient strips resting against said holder and having free terminals bearing against the holder at opposite sides of said opening for holding a film negative against said holder across said opening, a second pair of resilient strips resting against the aforesaid strips and having free terminals to bear against the aforesaid free terminals,

a mask to be held between the free terminals 15 of the two pairs of strip and having a restricted opening, members engaged through said strips and holder, and springs between said holder and members tending to hold said strips against the holder. 20

In testimony that I claim the foregoing as my own, I have hereto affixed my signature in the presence of two witnesses.

MONTE WELSH.
